United States Patent Office.

H. POOLE, OF RICHMOND, INDIANA.

Letters Patent No. 81,534, dated August 25, 1868.

IMPROVEMENT IN CULINARY VESSELS.

The Schedule referred to in these Letters Patent and making part of the same.

TO ALL WHOM IT MAY CONCERN:

Be it known that I, H. POOLE, of the city of Richmond, and State of Indiana, have invented a new and useful Improvement in Culinary Steamers; and I do hereby declare that the following is a full and exact description thereof, reference being had to the accompanying drawings, making a part of this specification, in which—

Figure 1 is a perspective view, and

Figure 2 a longitudinal vertical section.

The same letters in the different figures refer to corresponding parts of the invention.

My invention relates to an improvement in culinary steamers whereby the steam is generated in a chamber separate from that in which the cooking is done, by which means the steam may be controlled and admitted to different compartments of the steamer at pleasure.

To enable others skilled in the art to make and use my invention, I will proceed to describe its construction.

A represents a steamer divided by vertical partitions into cooking-chambers or compartments horizontally arranged with relation to each other.

D D are drawers supported on cleats at the sides of the chambers, the object of which drawers is to hold the articles to be cooked.

B is the pit of the steamer, and e represents a horizontal partition or false bottom, forming a boiler below.

C represents a lip or vent provided with a hinged lid, which vent serves as a safety-valve, and through which the boiler is supplied with water.

The partition e is inclined from the ends to the centre, so that any dripping of grease will run off and be discharged from spouts J J into any vessel placed to receive it.

u u are ports, through which the steam is admitted to the cooking-chambers.

I I are slide-valves for controlling the steam-ports, and are operated by means of handles n n.

t t are guides, through which said handles pass.

Other arrangements of the cooking-chambers may require different modifications for admitting the steam, when the compartments are arranged vertically with relation to each other. The steam may be conveyed up through a tube at the side or end of the steamer, which tube, being provided with a valve in each chamber, will thus also admit of the steam being directed on the different chambers at pleasure.

Having thus fully described my said invention, what I claim, and desire to secure by Letters Patent, is—

The steamer A, divided into compartments by one or more partitions, in which the boiler is separate from the cooking-chambers, and the steam is admitted to the latter at pleasure, as set forth.

H. POOLE.
